United States Patent

Des. 238,368

Patented Jan. 6, 1976

238,368

CALCULATOR

Alan B. Goldsamt, Banksville Road,
Greenwich, Conn. 06830

Filed Sept. 19, 1974, Ser. No. 507,531

Term of patent 14 years

Int. Cl. D18—01

U.S. Cl. D26—5 C

FIG. 1

FIG. 5

FIG. 2

FIG. 3

FIG. 4

FIG. 1 is a perspective view of a calculator showing my new design;

FIG. 2 is a top plan view thereof;

FIG. 3 is a side elevational view thereof;

FIG. 4 is a front elevational view thereof; and

FIG. 5 is a rear elevational view thereof.

The side of the calculator which is not shown is substantially identical to the side which is shown in FIG. 3. I claim:

The ornamental design for a calculator, as shown and described.
